UNITED STATES PATENT OFFICE.

LEIF LEE, OF YOUNGSTOWN, OHIO.

ROLLING MILL.

Application filed August 1, 1925. Serial No. 47,447.

The present invention relates broadly to the art of metal rolling and more particularly to improved rolling mills for use in rolling metallic sheets, although the utility 5 of the invention is not limited with respect to the particular material being handled, it being adaptable to other shapes as desired.

In sheet mills as used at the present time, several stands of rolls are usually connected 10 in line, each line including at least one two high roughing stand and one two high finishing stand with the rolls of the respective stands in substantial end to end relationship. The bottom roll of each stand is ordinarily 15 positively driven, bottom rolls in adjacent stands being customarily driven from one end through a spindle located intermediate the roll stands and supported in a suitable housing therebetween.

Union rules as at present in force provide 20 that when the distance between the centers of rolls in adjacent stands exceeds a predetermined amount, a single operator will not be permitted to make the throw from the 25 roughing pass to the finishing pass, it being necessary in such cases to use a helper. This constitutes what is known as a double throw mill and is obviously objectionable due largely to the number of operators required 30 for the rolling of the sheets. Where the distance does not exceed a predetermined minimum, the mill is referred to as a single throw, and a single operator may effect the transfer from one pass to the other.

At the present time two different types of 35 mills are utilized in both the single throw and the double throw class. In one type, the top rolls are not positively driven, but are caused to rotate by the friction of the entering 40 piece. Consequently, the thickness of the piece is limited to that which will enter the rolls. In the other type, the top rolls are positively driven in order to permit the use of a wider range in the thickness of the 45 pieces, and to insure that the pieces will enter the rolls quickly and surely.

It has heretofore been proposed to effect 50 the driving of the top roll, in mills of the second type, in many different ways. As illustrated for example in the patent of F. C. Biggert, Jr., No. 1,487,007 of March 18, 1924, one method embodies a floating housing with a friction drive between the lower and upper rolls. It has also been proposed to 55 effect this driving by means of an independent motor of comparatively low horse power

for the upper roll, the objection to such a construction however being the difficulty in mounting the motor together with the problems involved in the accurate control thereof. 60

The present invention relates particularly to an improvement in a drive of the character shown in the patent to F. C. Biggert, Jr., referred to and has for certain of its objects improvements therein of such nature as to 65 permit the use of a longer shaft for driving the upper roll, whereby the wear is correspondingly reduced, and also of means providing an improved mounting for the shaft.

In the accompanying drawings there is 70 shown for purposes of illustration only a preferred embodiment of the present invention, it being understood that these drawings do not define the limits of the invention as changes in the construction and operation disclosed therein may be made without departing from the spirit of the present invention or the scope of my broader claims. 75

In the drawings:

Figure 1 is a top plan view of a portion 80 of a rolling mill installation embodying the present invention;

Figure 2 is a vertical sectional view on the line II—II of Figure 1, certain of the parts being shown in elevation for sake of clearness; and

Figure 3 is a vertical transverse sectional view on the line III—III of Figure 1 looking in the direction of the arrows. 85

In carrying out the present invention, 90 there may be provided a rolling mill installation generally similar to that now employed and comprising a roll stand having a lower roll 2 and an upper roll 3. The roll 2 has operatively connected thereto a spindle 4 95 adapted to drive or be driven from the lower roll of an adjacent stand as shown, for example, in the patent referred to.

In accordance with this invention, the spindle 4 is mounted in a housing 5 of the 100 floating type, this housing having projections 6 adapted to receive bolts 7 depending from lugs 8 on a standard 9 supported on shoes 10 as understood in the art. Surrounding the bolts 7 are compression springs 11 105 the compression of which may be initially adjusted in any desired manner as by nuts 12. It will be understood by those skilled in the art that this construction permits the housing 5 to move relatively to the standard 9 as may be required by the operation 110 of the spindle 4.

Journalized in the upper part of the stand 9 on trunnions 13 is a yoke 14, the yoke having spaced bearings 15 for a drive shaft 16 mounted therein in substantial parallelism 5 to the spindle 4.

Secured in any desired manner to the spindle 4 is a gear 17 preferably having teeth 18 of curved contour to provide a driving engagement with a gear 19 the plane of 10 which may be angularly disposed to its own plane. This gear 19 has a similar tooth construction and is secured in any desired manner to a hub 20 carried by a casing 21 constituting part of a friction power transmitting means of any desired construction, but preferably of the type disclosed in my prior Patent No. 1,443,026 of January 23, 1923. As clearly disclosed in said patent, the casing 21 is adapted to frictionally drive the 15 hub 22 through suitable intermediate mechanism 23, the hub being secured to the shaft 16 in such manner as to effectively drive the same.

In operation, it will be apparent that the 20 spindle 4 constitutes a driving means extending between the lower rolls of adjacent roll stands and at the same time serves to drive the casing 21 and by means thereof frictionally drive the shaft 16 and the upper 25 roll 3. The gears 17 and 19 are so shaped as to maintain the desired driving engagement irrespective of the relative angular disposition thereof, whereby the gear 19 will be continuously driven in any angular positions assumed by the yoke 14 and the shaft 30 16. At the same time, the driving mechanism is so compactly arranged as not to necessitate any increase in the distance between the centers of adjacent roll stands. 35 This permits the maintenance of a single throw condition which is desirable for the 40 reasons pointed out.

Further advantages arise from the provision of a floating housing for the spindle 45 which connects the bottom rolls of adjacent stands and from an independently movable housing, in the form of a yoke, for the driving shaft for the upper roll.

Still other advantages arise from the increase in the effective length of the shaft 16 50 whereby the relative angular distance through which it moves for each variation in the position of the upper roll is correspondingly reduced. In this respect it will 55 be apparent that the driving shaft has an effective length equal to the distance from its driving connection with the upper roll to the axis of rotation of the yoke housing 14, this axis being substantially normal to the 60 axis of the shaft 16.

Still other advantages are obtained by reason of a shaft housing movable about trunnions and providing spaced bearings for rigidly supporting the shaft on opposite sides 65 of the axis of said trunnions.

I claim:

1. In a rolling mill, a spindle adapted to connect a roll in one stand with a roll in an adjacent stand, a floating housing for said spindle, a driving shaft, gearing between said spindle and shaft, and a tiltable housing for said shaft and at least a portion of the gearing, substantially as described. 70

2. In a rolling mill, a spindle adapted to 75 connect a roll in one stand with a roll in an adjacent stand, a floating housing for said spindle, a driving shaft, gearing between said spindle and shaft, and a movable housing for said shaft and at least a portion of the gearing, said movable housing 80 having supporting trunnions projecting therefrom, substantially as described.

3. A roll driving means for rolling mills, comprising a standard, a spindle housing movably carried thereby, a spindle in said housing, a shaft housing movably carried by said standard, a shaft journaled in said shaft housing and means carried by the housing for frictionally driving said shaft from said spindle, substantially as described. 85

4. In a rolling mill, a standard, a spindle housing movable relatively thereto, and a shaft housing journaled in said standard for rocking movement therein, said shaft housing having spaced bearings carried thereby, substantially as described. 90

5. A drive for rolling mills comprising a standard, a spindle mounted therein and adapted to drive a roll in the mill, a shaft housing carried by the standard, a shaft in the housing adapted to drive another roll in the mill, and a gear on the shaft operatively connected to the spindle, the shaft housing being tiltable about an axis lying substantially in the plane of the gear, substantially as described. 100

6. A drive for rolling mills comprising a standard, a spindle mounted therein and adapted to drive a roll in the mill, a shaft housing carried by the standard, a shaft in the housing adapted to drive another roll in the mill, and a gear on the shaft operatively connected to the spindle, the shaft housing being tiltable about an axis lying substantially in the plane of the gear, the gear teeth being convex in form, substantially as described. 110

7. In a rolling mill, a connection between two rollers having relative movement in a plane defined by their axes comprising a pivotally mounted supporting frame, a shaft and a friction clutch supported by the frame and movable therewith. 115

8. In a rolling mill, a connection between two rollers having relative movement in a plane defined by their axes comprising a pivotally mounted supporting frame, a shaft, a gearing wheel having convex teeth 120 125

and a friction clutch supported by the frame and movable therewith.

9. In a rolling mill, a connection between two rollers having relative movement in a plane defined by their axes comprising a pivotally mounted supporting frame, the axis of which is substantially at right angles

to the plane defined by the rollers, a shaft and a driving element therefor supported by the frame and movable therewith.

10

In testimony whereof I have hereunto set my hand.

LEIF LEE.
